Primary Examiner — Cathron C Brooks*Assistant Examiner* — Sharon S Oum(74) *Attorney, Agent, or Firm* — Heslin Rothenberg Farley & Mesiti P.C.; Victor A. Cardona, Esq.(57) **CLAIM**

I claim the ornamental design for a combined hairdryer and dock, as shown and described.

DESCRIPTION

FIG. 1 is a rear perspective view of a combined hairdryer and dock comprising the new design;

FIG. 2 is a right side view thereof;

FIG. 3 is a rear view thereof;

FIG. 4 is a bottom view thereof;

FIG. 5 is a front perspective view thereof;

FIG. 6 is a front view thereof; and,

FIG. 7 is a top view thereof.

The broken lines illustrate portions of the combined hairdryer and dock that form no part of the claimed design.
